UNITED STATES PATENT OFFICE.

JONATHAN A. HUNT, OF WESTBOROUGH, MASSACHUSETTS.

BICYCLE-SADDLE.

SPECIFICATION forming part of Letters Patent No. 613,927, dated November 8, 1898.

Application filed August 4, 1898. Serial No. 687,668. (No model.)

To all whom it may concern:

Be it known that I, JONATHAN A. HUNT, a citizen of the United States, residing at Westborough, in the county of Worcester and State 5 of Massachusetts, have invented certain new and useful Improvements in Bicycle-Saddles, of which the following is a specification.

My invention relates to saddles for bicycles, &c., and more particularly to saddles which 10 have a metallic base or foundation and a leather top or cover extending over the base with a cushion-surface intermediate.

It is essential in this class of saddles that the leather top or cover shall be securely attached to the metal base. Different ways of 15 attaching the leather cover to the base have been used, many of which are objectionable, as they are expensive and not attractive in appearance.

20 The object of my present invention is to provide an improved way of attaching the leather top or cover of the saddle to the metal base, which not only secures the cover to the base in a very strong and efficient manner, 25 but also presents an attractive appearance on the under side of the saddle.

My invention consists in certain novel features of construction of my improved saddle, and more particularly the manner of attaching 30 the leather top or cover to the base, as will be hereinafter fully described.

Referring to the drawings, Figure 1 is a plan view of a saddle embodying my improvements. Fig. 2 is a bottom view of the saddle 35 shown in Fig. 1. Fig. 3 is a cross-section on line 3 3, Fig. 1, looking in the direction of arrow *a*, same figure; and Fig. 4 shows a portion of the under side of the metal base and a portion of the attaching leather strip 40 cured thereto.

In the accompanying drawings, 1 is the leather top or cover of a saddle, which forms the upper surface of the saddle. The edges of the leather top or cover 1 extend down- 45 wardly around the edge of the saddle, as shown in Fig. 3.

2 is the metal base or foundation of the saddle, which is preferably made with a central longitudinal extension 2' on the lower surface 50 thereof to receive the central depressed portion 1' of the top or cover 1, which is held

therein in this instance by means of a metal plate 3 and rivets 4. Holes 3' may extend through the central depressed portion. A corrugation or rib 5 preferably extends around 55 the metal base 2, near the edge thereof, upon the under side to strengthen or make more rigid the base 2. (See Fig. 2.)

Two holes 6 are made in the base 2, in which are secured washers 7, screw-threaded internally to receive the attaching-screws of the spring. (Not shown.)

Around the outer edge of the base 2 are formed by stamping or cutting out the metal a series of attaching hooks or binders 8, which 65 are first made, as shown at the upper part of Fig. 4, to project upwardly with their ends curved or bent outwardly.

A strip of leather 9 or other suitable material extends around upon the inner edge of 70 the base 2, and the inner edge of said strip 9 extends under the hooks or binders 8 and the outer edge extends beyond the edge of the metal base 2, as clearly shown in Fig. 4. To attach the strip 9 securely to the base 2, the 75 hooks or binders 8 are flattened or pressed down and their ends forced into the strip 9.

Between the leather top or cover 1 and the base 2 a cushion-surface 10, of any suitable material, as hair, or, if preferred, an air-cush- 80 ion, extends, as shown in Fig. 3. The leather top or cover 1 is secured to the base 2 by securing the edge of said cover to the projecting edge of the strip 9; preferably by stitching 11, as shown in the drawings. In this 85 manner the leather top or cover 1 is securely attached to the metal base or foundation 2 by means of the strip 9, which in turn is securely attached to the metal base 2 by the hooks or binders 8, as above described. 90

The advantages of my improved construction of saddle, particularly the manner of attaching the leather top or cover to the metal base or foundation, will be readily appreciated by those skilled in the art. 95

By suitable stamps or dies the metal base is cut out and pressed into the desired shape with the attaching hooks or binders 8 formed thereon and made integral therewith. The leather strip 9 is then attached to the edge of 100 the metal base by the hooks or binders 8 and the leather top or cover 1 sewed to the outer

edge of the strip 9 in a suitable machine, so that the under surface of the saddle presents an attractive appearance.

It will be understood that the details of construction of my saddle may be varied somewhat, if desired, and the outer rim or edge of the saddle may extend downwardly to form a flange or rim, as shown in Fig. 4, or may be flattened outwardly, as shown in Figs. 2 and 3.

Having thus described my invention, what I claim as new, and desire to secure by Letters Patent, is—

1. In a bicycle-saddle, the combination with a metal base having a series of hooks or binders formed thereon around the edge thereof, and a strip of leather or other suitable material secured to the edge of said base by said hooks or binders, of a leather top or cover secured to said strip, substantially as shown and described.

2. In a bicycle-saddle, the combination with a metal base or foundation, with a central de-

pressed portion, and a series of hooks or binders formed thereon around the edge thereof, and a strip of leather or other suitable material secured to the edge of said base by said hooks or binders, of a leather top or cover secured to said strip, substantially as shown and described. 25

3. In a bicycle-saddle, the combination with a metal base or foundation, having a central depressed portion, and a corrugation or rib near the edge of the base, and a series of hooks or binders formed thereon, and a strip of leather or other suitable material secured to the edge of said base by said hooks or binders, of a leather top or cover secured to said strip by stitching, substantially as shown and described. 30

JONATHAN A. HUNT.
